UNITED STATES PATENT OFFICE.

LOUIS P. GRIFFIN, OF PROVIDENCE, RHODE ISLAND.

SUSPENSORY-BANDAGE.

SPECIFICATION forming part of Letters Patent No. 291,592, dated January 8, 1884.

Application filed August 23, 1883. (No model.)

To all whom it may concern:

Be it known that I, LOUIS P. GRIFFIN, of the city and county of Providence, and State of Rhode Island, have invented a new and useful Improvement in Suspensories; and I do hereby declare the following specification, taken in connection with the accompanying drawing, forming a part of the same, to be a description thereof.

10 It consists in providing the sack with an elastic loop, through which may pass loosely a tape to be secured to the waistband to hold the sack in its proper position, as will herein-after appear, and in certain other details of construction set forth in the claims.

15 The drawing illustrates in perspective my improved suspensory viewed from the rear.

A is the sack or net-work which receives the scrotum. B is the waistband, which is 20 provided with two depending straps, b b, secured thereto by stitching, by eyelets, or in any preferred manner. The sack A is furnished with buckles C C, which engage said straps and adjustably and detachably secure the sack to the waistband. If preferred, however, the sack may be provided with straps and the waistband with buckles, or equivalent means 25 may be employed by which the sack A shall be adjustably and detachably secured to the band B.

30 For retaining the sack A in proper position when on the body, a tape, D, is provided, which is intended to pass rearwardly between the legs of the wearer. This tape is secured at its ends to loops b' b' on the band B, which loops are preferably elastic, and are located about at the hips of the wearer. The central portion of the tape D passes through a loop, a, which

is secured to the sack A. The tape loosely occupies this loop in order that it may slide 40 therein, and thereby allow the legs to move freely without causing inconvenience; and said loop a is made elastic, in order that all undue pressure upon the urethral track may be avoided and still greater freedom of movement to the body be allowed.

The advantages of making the sack adjustable upon the waistband are that the suspensory can be readily adjusted properly to fit the wearer, that it may be used as a compress 50 in the case of the swelled testicles, and for holding medicated applications. By making the sack detachable it may be partially or wholly removed from the band as the convenience of the wearer may at times demand, 55 and can be removed in order that it may be cleansed. It also allows of the substitution of sacks of the same or different sizes.

What I claim, and desire to secure by Letters Patent, is—

1. A suspensory having a waistband, a sack attached thereto, and provided at its lower edge with an elastic loop, a, and a tape adapted to pass loosely through said loop, and to be secured to the waistband, substantially as set 65 forth.

2. A suspensory having its sack adjustably and detachably secured to its waistband, and provided with an elastic loop, a, adapted to receive loosely a holding-tape, substantially 70 as set forth.

LOUIS P. GRIFFIN.
